UNITED STATES PATENT OFFICE.

ROGER SHERMAN HOAR, OF SOUTH MILWAUKEE, WISCONSIN, ASSIGNOR TO BUCYRUS COMPANY, OF SOUTH MILWAUKEE, WISCONSIN, A CORPORATION OF WISCONSIN.

ROPE-THRUSTING SHOVEL.

Application filed February 3, 1923. Serial No. 616,688.

To all whom it may concern:

Be it known that I, ROGER SHERMAN HOAR, a citizen of the United States, residing at South Milwaukee, in the county of Milwaukee and State of Wisconsin, have invented a certain new and useful Improvement in Rope-Thrusting Shovels, of which the following is a full, clear, concise, and exact description, reference being had to the accompanying drawings, forming a part of this specification.

This invention relates to power shovels of the type in which thrusting or shifting of the dipper handle is effected by cables actuated and controlled from the main frame.

The general aim of the present invention is to simplify and improve the construction and operation of shovels of this character.

A more specific object is the provision of a novel application of the hoisting cable directly upon the dipper handle whereby the working tension therein may be utilized to produce a powerful end thrust upon the handle.

Another object is the provision of a novel and improved mounting for the dipper handle.

Other objects and advantages will appear from the following description of an illustrative embodiment of this invention.

In the drawings:

Figure 1 is a side elevation of the excavating mechanism of a power shovel constructed in accordance with the present invention.

Figure 2 is a detail of the mounting of the dipper handle as it would appear looking downwardly lengthwise of the handle.

Figure 3 is a side elevation of a shovel similar to that of Figures 1 and 2 illustrating a different arrangement of cables.

Figure 4 is a view similar to Figure 3 illustrating a modified mounting for the dipper handle and a modified arrangement of cables.

Figure 5 is a sectional view taken substantially along the line 5—5 of Figure 4.

The shovel illustrated in Figures 1 and 2 includes the usual operating frame or platform 10 having a boom 11 mounted to swing about a horizontal pivot 12, carried by the frame and supported in any desired position of inclination by the cable 13 in the usual manner. The boom shown is composed of a pair of channel bars 11' spaced

apart to receive the dipper handle 14 therebetween. The dipper handle is in the form of an I-beam carrying at its outer end the usual dipper 15.

The dipper handle is mounted for lengthwise shifting movement in a rock frame 16, comprising triangular side plates 17, rigidly connected by stub shafts 18 carrying bearing rollers 19 and 19'. This frame is pivotally supported upon trunnions 20 connected to the side plates and journaled in bearing brackets 21 fixed to the boom. The dipper handle extends through the rock frame beneath the upper bearing roller 19' and rests upon the lower bearing rollers 19. It will be noted that the trunnions 20 are disposed intermediate the upper and lower bearing rollers so that the frame 16, and consequently the dipper handle, rocks about an axis which intersects the path of lengthwise shifting of the handle. Any binding action between the handle and rock frame is thus avoided.

The dipper handle is normally restrained against outward shifting movement by a cable 22 which, in this instance, is shown anchored at 23 to the dipper handle adjacent the outer end thereof. Cable 22 passes over a sheave 24 journaled upon one of the trunnions 20 and is actuated and controlled by a drum 25 to which it is secured.

The dipper handle is biased toward outward shifting movement by the working tension in the dipper hoisting cable 26. In the shovel shown in Figures 1 and 2, this cable extends from a hoisting drum 27 over a sheave 28 mounted adjacent the outer end of the boom, thence downwardly beneath a dipper supporting padlock sheave 29, along the dipper handle to and around a sheave 30 carried adjacent the inner end thereof, and then to a swinging anchorage 40 on the other of the trunnions 20 to which it is secured. Thus, the hoisting cable not only serves to support the dipper, but the resulting tension therein, through that portion thereof adjacent the sheave 30, produces an outward endwise thrust upon the dipper handle. By reason of its connection with the trunnion 20, all flexing or bending of the cable adjacent that point, due to swinging of the handle, is avoided. It will also be noted that that portion of the cable between the trunnion 20 and the sheave 29 is so arranged as to swing with the dipper handle

about the axis of the trunnion as a center, without relative motion between the handle and cable, thus avoiding friction and consequent wear between the cable and sheave 30 due to swinging of the handle.

The drums 25 and 27 are shown coaxially arranged upon the main operating frame 10. They are independently actuated from a single prime mover (not shown) through a 10 constantly moving shaft 43. A clutch member 42 slidably keyed to this shaft, for selective engagement and disengagement with drum 27 is conventionally shown in Figure 1. A brake 41 for drum 27 is conventionally shown in Figure 1. A similar clutch and brake exist for drum 25, but are not shown.

To illustrate the operation of the shovel described, assume that the dipper is in the lower digging position, as indicated by dotted 20 lines in Figure 1, and that the drum 25 is held by its brake against rotation. Upon rotation of the hoisting drum 27 in a counter-clockwise direction, the hoisting cable 26 is drawn in, the dipper is raised, and the 25 dipper handle swung about the axis of trunnions 20 as a center. If it is desired to force the dipper deeper into the bank or to shift the dipper to an outer extreme position for dumping purposes, this may be accomplished 30 by merely releasing the drum 25 so as to pay out the cable 22 and thus permit the dipper handle to shift outwardly under the pressure of the hoisting cable 26 against the sheave 30. Similarly, to shift the handle 35 inwardly, it is only necessary to rotate the drum 25 in a counter-clockwise direction so as to draw in the cable 22 against the thrusting influence of the hoisting cable. Thus it will be noted that the thrusting 40 action of the dipper handle is always under the complete control of the drum 25 irrespective of the operating condition or action of the hoisting drum and cable.

The shovel illustrated in Figure 3 is similar in many respects to that hereinabove 45 described. It includes a split boom 11 having a dipper handle 14 extending therethrough, the dipper handle being slidably mounted in a similar rock frame 16 pivotally mounted as at 20 upon the boom. In this instance, however, the hoisting cable 26 is reeved two part. After passing over the usual sheave 28 at the upper end of the boom and beneath the dipper supporting 50 padlock sheave 29, it is returned over a second sheave at the upper end of the boom, similar to sheave 28, and from thence extends beneath a sheave 31 journaled upon the rock frame 16, over the sheave 30 carried 55 by the inner end of the dipper handle and is anchored as at 32 upon the rock frame.

As in the shovel hereinabove described, the tension in that portion of the hoisting cable 26 adjacent the sheave 30 tends at 60 all times to thrust the dipper handle out-

wardly. This thrusting action is controlled and inward thrusting effected by a cable 22 anchored as at 23 to the dipper end of the dipper handle and passing over a sheave 33 carried by the rock frame. Sheaves 31 70 and 33 are so disposed as to cause the cables 26 and 22, respectively, to pass substantially across or adjacent the pivotal axis 20 of the dipper handle in all angular positions thereof so as to avoid any material lengthwise movement of these cables toward or from that axis due to swinging of the handle. Thus, as in the shovel above described, the thrusting portion of the hoisting cable 75 swings with the dipper handle about the pivotal axis thereof without relative motion between that cable portion and handle due to swinging of the handle. Wear between the hoisting cable and sheaves 30 and 31 is thus reduced to a minimum. 80

The shovel illustrated in Figures 4 and 5 comprises a boom 11' carrying a bifurcated dipper handle 14' straddling the boom. Each leg of the dipper handle is slidably mounted between cooperating bearing rollers 90 34 carried by a rock frame 16'. Frames 16' are supported upon the ends of a shaft 20' fixed in brackets 21' carried by the boom.

The hoisting cable 26' extends from the hoisting drum (not shown) beneath a sheave 95 35, journaled on the shaft 20', over a sheave 30', journaled between the legs of the dipper handle at the inner end thereof, beneath a second sheave 36, journaled on shaft 20', thence over a sheave 28', at the upper end of 100 the boom, down beneath the dipper supporting padlock sheave 29' and finally back to the upper end of the boom where it is anchored as at 37.

As in the shovels hereinabove described, 105 the tension in that portion of the hoisting cable between sheave 30' and sheaves 34 and 35 tends at all times to thrust the dipper handle outwardly. This thrusting action is controlled and inward thrusting effected by 110 a cable 22' anchored as at 23' to the dipper end of the dipper handle and passing over a sheave 38 journaled on the shaft 20'. It will be noted that the thrusting portion of the hoisting cable is arranged to swing with 115 the dipper handle so as to avoid any whipping action of the cable against the sheave 30' during swinging of the handle.

Various changes may be made in any of 120 the embodiments of the invention hereinabove specifically described, without departing from or sacrificing any of the advantages of the invention as defined in the appended claims.

I claim:

1. In a power shovel, the combination of 125 a support, a dipper and dipper handle mounted thereon for swinging and shifting movements, a dipper hoisting cable having a portion associated with said dipper handle 130

- at a fixed point thereof, to shift said handle, said portion extending substantially the entire length of said dipper handle in all its positions and being arranged to swing with 5 said dipper handle about the pivotal axis thereof as a center and means for controlling such shifting movement.
2. In a power shovel, the combination with a supporting boom, of a dipper and 10 dipper handle mounted thereon to move lengthwise and swing with respect thereto, a single part hoisting and thrusting cable associated with said dipper and dipper handle and pulling directly thereon for 15 crowding the dipper, and means distinct from said cable for moving said dipper inwardly.
3. In a power shovel, the combination with the supporting boom, of a dipper 20 handle carried by said boom for swinging and shifting movements relative thereto, a hoisting drum, a hoisting and thrusting cable connected with said drum, dipper and boom, comprising a single hoist line portion 25 from the drum to said boom and dipper, and a bight in said line in end-thrust engagement with the dipper handle, said cable being connected beyond said bight with the boom, and separate means for moving said 30 dipper inwardly.
4. In a power shovel, the combination with the supporting boom, of a dipper handle carried by said boom for swinging and shifting movements relative thereto, a hoisting drum, a sheave on the outer end 35 portion of the boom, sheaves on the upper and lower end portions of the dipper handle, a hoisting and thrusting cable passing from said drum over the sheave on the boom, thence around the lower sheave on the handle, thence over the 40 upper sheave on the handle, and thence to the boom, and a bight in end-thrust engagement with the dipper handle, said cable being connected beyond said bight with the boom, and another cable for moving the dipper 45 per inwardly toward the boom.
5. In a power shovel, the combination with the supporting boom, of a dipper and dipper handle mounted thereon to shift and swing with respect thereto, a dipper hoisting and thrusting cable having a single 50 hoist line connection with the dipper and having a bight in end-thrust engagement with said dipper handle for crowding the dipper, and a separately controlled cable 55 for moving said dipper inwardly.
6. In a power shovel, the combination with the supporting boom, of a dipper handle carried by said boom for swinging and shifting movements relative thereto, a hoist- 60 ing drum, a sheave on the boom, sheaves on the upper and lower end portions of the dipper handle, a hoisting and outward thrusting cable passing from said drum over the sheave on the boom, thence around the lower sheave on the handle, thence over the 65 upper sheave on the handle, and thence to the boom, and having a swinging anchorage connection with said boom, and separate means for moving the dipper handle inwardly. 70
7. In a power shovel, the combination with a supporting boom, of a dipper and dipper handle mounted thereon to move lengthwise and swing with respect thereto, an odd part hoisting and thrusting cable 75 associated with said dipper and dipper handle and pulling directly thereon for crowding the dipper, and means distinct from said cable for moving said dipper inwardly. 80
8. In a power shovel, the combination with the supporting boom, of a dipper and dipper handle mounted thereon to shift and swing with respect thereto, a dipper hoisting and thrusting cable having an odd part connection with the dipper and having a bight in end-thrust engagement with said dipper handle for crowding the dipper, and a separately controlled cable for moving said dipper inwardly. 85
9. In a power shovel, the combination 90 with the supporting boom, of a dipper handle carried by said boom for swinging and shifting movements relative thereto, a hoisting drum, a hoisting and thrusting cable connected with said drum, dipper and boom, comprising a hoist line portion with an odd 95 number of reaches from said boom to said dipper, and a bight in said line in end-thrust engagement with the dipper handle, said cable being connected beyond said bight with the boom, and separate means for moving said dipper inwardly. 100
10. In a power shovel, the combination of a boom, a frame, a dipper handle mounted for lengthwise reciprocation in said frame, 105 means for supporting said frame on said boom to permit said frame and handle to swing about an axis passing through said handle, two bearing rollers below said handle carried by said frame and positioned 110 from each other in the direction of the length of said handle, a guide roller above said handle carried by said frame, and means for swinging and shifting said handle. 115

In witness whereof, I hereunto subscribe my name this 30th day of January, 1923.

ROGER SHERMAN HOAR.
